UNITED STATES PATENT OFFICE.

EARLE E. SCHUMACHER, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE AND CIRCUIT THEREFOR.

Application filed October 22, 1924. Serial No. 745,085.

This invention relates to electron discharge devices and has for an object to eliminate the need of an independent heating means for the cathode of such devices 5 after the space discharge has been established between the cathode and anode.

This object is attained by utilizing as the cathode of the device, a filamentary core which may be of highly refractory metal, 10 provided with a thick shaggy coating of thermionically active material, such as alkaline earth oxides. After a space discharge has been established between the cathode and anode of the device, the cathode heating means may be discontinued without 15 material diminution of the space current, provided a sufficiently high potential is maintained between the cathode and anode. This arrangement eliminates one source of 20 power without preventing the continued emission from the coated cathode to the anode.

Referring to the drawings:

Fig. 1 shows diagrammatically a circuit 25 for carrying this invention into effect.

Fig. 2 is a V-shaped filament for an electron discharge device with a portion broken away to show the relative thickness of the core and the active coating.

In carrying this invention into effect, a 30 highly refractory filament core 10, such as tungsten, molybdenum or the like, is heated to a high temperature, in vacuum, and finely powdered, thermionically active material brought in contact with the refractory core, 35 to provide a thick and shaggy coating 11, having high electron emissivity.

A cathode of this character may be obtained by supporting a refractory core 10 in 40 a glass vessel 12 containing a grid 13 and a plate electrode 14. A quantity of powdered material of high thermionic activity, such as barium and strontium oxides is placed in the vessel and the vessel highly evacuated and 45 sealed off in the usual manner. A power source of sufficient voltage, is connected to the filament leads and the filament core heated to a suitable temperature, which in the case of barium and strontium oxides is 50 between 700° and 1000° C. The vessel is then shaken to bring the thermionically active material into contact with the heated cathode core and this operation is continued until the particles of thermionically active

material have been taken up by the cathode, 55 to provide a relatively thick coating. The thickness of the coating obtained in this way depends upon the temperature of the filament core, and also upon the degree of vacuum obtained in the device, which may be 60 approximately of a pressure of 1×10^{-4} mm. Hg. or less. After the desired thickness of coating has been obtained, the tip of the glass vessel may be broken and the excess material removed and the vessel again 65 evacuated and sealed. Due to this method of coating, the thermionically active material adheres to the incandescent core of the filament and forms a thick, shaggy coating 70 having a surface which is composed of minute points or edges, giving the filament coating a rough appearance. This method is described and claimed in my copending application, Serial No. 650,985, filed July 12, 1923 entitled "Electron emitting cathodes 75 and method for making them".

However, other methods may be used which will produce a thick and highly lacinated coating on the refractory filament core. The coating obtained in this manner 80 has good thermionic properties and does not deteriorate readily.

A plurality of leads 15, are attached to the electrodes within the vessel and are sealed within the press 16 of the vessel 12. The filament or cathode 10 is connected to a battery 17, through conductors 18 and 19, and a switch 20, by means of which the battery 17 may be disconnected from the filament 10. The control electrode 18 is connected to the cathode by conductor 21, the secondary winding of the input transformer 22, and battery 23 which maintains the control electrode negative with respect to the filament. The plate electrode 14 is connected to the cathode by conductor 24 through the primary winding of the output transformer 25, and battery 26 which impresses a difference of potential between the cathode 95 and anode.

The method of operation consists of closing the switch 20, whereupon heating current is supplied to the filament. Simultaneously, a space discharge is established between the cathode and the anode by the battery 26, 100 which may be between 250 and 500 volts, or sufficient to heat the anode to a red glow. The switch 20 may be opened immediately

without discontinuing the operation of the device, and the electron emission from the filament will continue as long as the voltage of the plate battery is sufficiently high. The dissipation of energy in the coating by the flow of space current therethrough maintains it sufficiently hot to cause the emission of electrons.

By this arrangement, an electron discharge device containing a cathode having a thick and shaggy coating may be utilized in a variety of circuits such as, detectors, amplifiers, oscillators and repeater circuits, and maintain continuous electron emission from the cathode over a considerably long period of time without being supplied with a continuous heating current from a separate battery.

Although the invention has been described with reference to a particular arrangement, it is, of course, understood that various modifications may be made in the construction and method of operation without departing from the scope of the invention as covered in the appended claims.

What is claimed is:

1. In combination an electron discharge device having a cathode and an anode, an

output circuit comprising said cathode, anode and a source of current, and a source of heating current for said cathode, said cathode comprising a metal core having a thick shaggy thermionically active coating, means for closing said heating circuit to establish the space current flow between said cathode and anode, and for thereafter opening said heating circuit, the dissipation of energy in the coating by the flow of space current therethrough maintaining the same sufficiently hot to cause it to emit electrons. 40

2. In combination an electron discharge device comprising a cathode and an anode, an output circuit therefor containing a source of current, a source of heating current for said cathode, and means for disconnecting said cathode source, said cathode comprising a filament having a thick shaggy coating, the dissipation of energy in the coating by the flow of space current therethrough maintaining the same sufficiently 50 hot to cause it to emit electrons.

In witness whereof, I hereunto subscribe my name this 18th day of October, A. D. 1924.

EARLE E. SCHUMACHER.
